PYROTECHNIC DEVICE

Herbert C. Clouser and Robert S. Long, Westerville, Ohio, assignors, by mesne assignments, to Kilgore, Inc., Westerville, Ohio, a corporation of Ohio

Application May 24, 1947, Serial No. 750,246

1 Claim. (Cl. 102—7)

This invention relates to pyrotechnic devices, and more particularly to a buoy adapted to eject a projectile containing a signal such as a parachute flare.

One of the objects of this invention is to provide a pyrotechnic device in which there is a casing adapted to be dropped from an aircraft into water, the casing being sufficiently buoyant to float in an upright position, and which also contains means for discharging a projectile supporting a signal, such as a parachute flare, from its position in the water.

Another object is to provide a pyrotechnic device of the character described in which the assembly includes a casing adapted to be dropped into water from an aircraft, for example, the casing being sufficiently buoyant to float in an upright position, and which contains a mortar for discharging from the casing into the air a projectile having a signalling means, such as a parachute flare, operating to indicate or illuminate the position of the floating casing.

An additional object is to provide a pyrotechnic device having an elongated casing which is open at the top and has a mortar sealed therein, an air chamber also being formed therein so that the assembly can be dropped into a body of water and float in an upright position from which a projectile containing a signal can be fired to indicate the location of the floating device.

It is also an object to provide a device of the character described in which there is a mortar having a projectile arranged in an ejectable position therein, the base of the projectile having a pocket for a propelling charge of powder and a rupturable wall over the pocket, there also being a signal means carried within the projectile and an expelling charge therefor so that when the projectile is expelled from the mortar the upper wall of the base of the projectile provides a means for separating the expelling charge for the signal means from the propelling charge for the projectile.

Further objects and advantages of this invention will be apparent from the following description, the appended claim, and the accompanying drawings in which a preferred form of one embodiment of the present invention is shown.

In the drawings:

Fig. 1 is a view in elevation, which is broken as indicated, illustrating a pyrotechnic device embodying one form of the present invention;

Fig. 2 is a view in vertical section through the device of Fig. 1, taken substantially on the center line and at right angles as seen therein;

Fig. 3 is a view partially in vertical section and in elevation, on a larger scale than in Fig. 1, of a portion of the mortar and projectile shown in Fig. 2;

Fig. 4 is a view in vertical section, on a larger scale than in Fig. 3, of the lower or base portion of the device illustrated in Fig. 2; and

Fig. 5 is a plan view of the fin construction employed in connection with the device of Fig. 2.

Referring to the drawings, the pyrotechnic device 21 shown includes a cylindrical casing 22 having a head 24 and base 25. The head 24 and the base 25 are secured to the casing 22 by a plurality of screws 27. A fin assembly 28 is attached to the head 24 by screws 29. Suspension bands 31 surround the casing 22 and are provided with openings 32. A cable (not shown) passes through the opening 32 for securing the pyrotechnic device to an aircraft for example. An igniter 33 extends through the wall of the head. This igniter 33 is preferably of the Bouchon type, the operation of which is explained in detail in applicants' co-pending application Serial No. 691,008, filed August 16, 1946. The igniter 33 is provided with a ring 34 that has a cable passed therethrough which is attached to the aircraft.

A mortar 35 is disposed within the casing 22 which comprises a mortar base 37 anchored to the buoy base 25 by the screws 38, and a cylindrical tube 39 is threaded into the threaded opening 40 in the motor base 37. The upper end of the tube 39 extends through an opening in the casing head 24 and is threaded to receive a collar 43. When the collar 43 is drawn tightly onto the top of head 24, it forms a seal to prevent the ingress of water into the casing 22 and also firmly holds the upper part of the tube 39 in position.

A projectile 45, Fig. 3, disposed within the mortar tube 39 includes a base 46 and a metal shell or cylindrical tube 47. A parachute 49 is contained within the upper part of the tube 47 and a candle 50 is carried in the tube below the parachute. The parachute is provided with a chord 51 which is connected with a metallic cable 52 to the upper portion of the candle 50. The parachute 49 is folded in a thrust cylinder 53 formed of heavy cardboard.

The candle 50 comprises a cylindrical casing 55 formed of heavy cardboard which is covered with a zinc sheathing 56. The upper end of the candle is covered by a cap 58 which is secured to the cardboard by screws 59. The end of the folded cable 52 is suitably connected to the cap. The lower end of the casing 55 and the sheath

56 therefore extends within a circular groove 61 in the top side of a steel ring 62. A zinc disc 63 having a central opening 64, is soldered to the bottom base of the ring or collar 62. A number of strands of quickmatch 66 extend across the opening 64 and a thin layer of readily ignitable black powder 67 is disposed on the disc 63. A layer of readily ignitable but slow burning powder is disposed above the black powder 67. This readily ignitable but slow burning powder 68 ignites the candle material 70 which is interposed substantially throughout the length of the casing 55 between the powder 68 and a cylindrical block of clay 71. The upper end of the tube 47 is closed by a cap 73 which is held in place by tape 74. A cardboard disc 75 is interposed between the upper end of the cylinder or sleeve 53 and the cap 73.

The candle 50 and the parachute 49 are forcibly ejected through the upper end of the tube 47 by the expansion of gases below the zinc disc 63. The steel ring or collar 62 prevents the mutilation of the bottom of the candle when the gas there below expands. When upper movement is imparted to the candle 50, this movement will be imparted to the parachute 49 and the cylinder or sleeve 53 through a heavy felt disc 77 which is interposed between the candle and the parachute and sleeve. The upward movement of the sleeve 53, through the disc 75, forces the cap 73 off of the end of the tube 47 whereby the candle and parachute are expelled from the tube 47. The cardboard casing or sleeve 53 of the candle 50 is sufficiently stable to prevent mutilation of the candle while it is being ejected and the sleeve 53 functions as a thrust member for protecting the parachute 49. The felt disc 77 interposed between the parachute and the candle 50 functions as a fire wall to prevent any burning gases which may surround the candle 50, during the ejection thereof, from igniting the parachute.

The base 46 of the projectile 45 includes a bottom plug or cap 78 having the upper end thereof suitably secured in the bottom end of tube 47. A recess is formed in the top of the plug 78, providing a pocket 79 for an expelling charge of powder 80. A rupturable disc 76 covers the pocket 79. A cushioning disc 81 rests upon the disc 76, said disc being known as a setback wad and is preferably formed of pressed ground cork. The disc 63 of the candle case rests upon the cushioning disc 81. Cushioning disc 81 is for the purpose of absorbing some of the shock which is imparted to the candle case when the expelling charge 80 is ignited.

When the expelling charge 80 is ignited, the expanding gases will rupture the disc 76, and drive the cushioning disc 81 upwardly to cause the candle 50 and the parachute 49 to be ejected as previously explained. A central hole 82 is formed in the disc 81 so that the strands of quickmatch 66 are subjected to the fire of the expelling charge 80. As the candle and parachute are expelled from the projectile tube 47, the candle material will be ignited through the burning of powder 68, the powder 68 being of such character as to expel and ignite the candle material 70 at the same time. The expelling and igniting actions thus being substantially simultaneous.

The plug 78 includes a downwardly extending shank 83 which merges from a large portion 84 to a smaller portion 85. The large portion 84 is exteriorly threaded as at 86 onto which is

threaded a container 87. A metallic cover 88, such as sheet copper, surrounds the container 87, the lip 89 thereof covering the top of the container. The container 87 can be drawn tightly onto the plug 78 through the threads 86 and constitutes a seal, no additional sealing washer being required between the top side of the lip 89 and the bottom of the plug. A ring 91, having the general contour of the upper corner of the container 87 and the cover 88, on its under side, and being flat on its top side to conform to the bottom of the plug 78, is interposed between the cover 88 and the bottom of the plug 78 and is utilized for preventing distortion of the cover 88 i. e., to such an extent as would allow the gases generated from the burning of the propelling charge from blowing out along the top of the cover 88. This ring 91 formed with an inner feather edge 90 is fastened in position when the container 87 is threaded into position.

The container 87 is hollowed out to form a pocket 92 for a charge of propelling powder 93. The bottom 94 of the container 87 is provided with a plurality of holes 95 and the bottom sides of these holes are closed by a rupturable disc 96 which is preferably formed of lead. The shank portion 85 of plug 78 extends through the pocket 92 and through the bottom 94 of the container 87 and is threaded as at 97. A circular and inwardly extending lip 99 at the bottom of the cover 88 covers part of the bottom 94 of the container 87 and this lip 99 and the disc 96 are held in position by a cap 101. This cap has a central opening 102 surrounding the shank 85 of plug 78 and is held in position by a nut 103 threaded onto the thread 97 of the shank 85. Cap 101 is provided with a plurality of openings 105 which are aligned with the holes 95 in the bottom 94 of container 87.

The central portion of the plug 78 is provided with aligned bores 106 and 107, the upper bore being somewhat smaller in diameter than the lower. The upper bore 106 leads to the recess or pocket 79 while the lower bore extends through the lower part of the shank and is threaded at 108. A time delay fuse 109 is disposed within the bore 106 and extends within the pocket 79 and within the powder 80. This time delay fuse is contained within a brass fuse housing shouldered at the bottom to retain it within the vertical opening of bore 106 as shown in Fig. 4. This housing is provided with a series of small restricted openings 110 extending laterally through the cup within the upper portion thereof, and which communicate with the powder 80 within the pocket 79, the fuse being adapted to ignite the powder 80 through said openings 110. The cartridge 111 is held in position by a sleeve 113 which in turn is held in position by a lock screw 114. Sleeve 113 seats at its upper end against the shoulder portion of the fuse housing 109 to retain the latter in position. A series of transverse holes 115 in the sleeve 113 are aligned with a series of transverse holes 116 in the shank portion 85 of the plug 78 for connecting the interior of the sleeve 113 with the powder 93 in pocket 92. The sleeve 113 and the holes 115 and 116 are filled with a black powder 117 and the outer ends of the holes 116 are closed by a tape 118, of paper or the like, for retaining the powder 117 within the holes. A quickmatch fuse 120 extends within the lower part of the sleeve and is surrounded by black powder 117. This quickmatch 120 is adapted to be ignited by a safety fuse 122 which extends

through the lower part of bore 123 and is held in position by a collar 124 threaded into threaded portion 108 of the bore 107. The safety fuse 122 is preferably of the Ensign-Eickford type that burns at the rate of approximately a foot per five (5) seconds. The fuse extends through an opening in the mortar base 37 and is wound spirally about the cylindrical tube 39 and the upper end thereof is connected with the igniter 33.

When the powder 117 is ignited by the quickmatch 120 through the fuse 122, the tapes 118 closing the holes 116 leading to the powder 93 in pocket 92 are burned away. This will cause the ignition of the expelling charge 93. The expansion of the gases due to the ignition of the charge 93 will rupture the disc 96, and the expanding gases escaping through the holes 105 in the cap 101 are confined within the tube 39 and the anchor 37 and will cause the entire projectile 45 to be ejected through the top of the tube 39. The side walls of the container 87 are provided with a series of openings 125 which are covered by the metallic cover 88. The expansion of the gases with the burning of the charge 93 will expand cover 88 into sealing engagement with the interior wall of the mortar tube 39 so as to confine the gases to below the projectile.

The casing 22 must be of sufficient length to assure buoying of the entire device 21 and since it is necessary to seal the interior of the casing 22, the mortar tube 39 must extend to the top of the head 24. The overall length of the mortar tube 39 is therefore greater than the length of the projectile 45. The projectile 45 is retained in the bottom portion of the mortar tube 39 by a cylindrical sleeve 127 formed of heavy cardboard resting upon a wooden block 128 which in turn rests upon the top of the projectile. The top of the projectile mortar tube 39 is closed by a wooden plug 129 received within the end of the tube with a slip fit. To seal the end of the mortar tube and prevent it from taking water, a thin zinc disc 131 is soldered across the inside diameter on top of plug 129. This sealing disc is secured in such manner to the end of the mortar tube that a shipping cap 130 can be threadedly received thereon, as shown in Figure 2, and screwed down to afford protection during transportation. Such shipping cap is removed when the device is being made ready for attaching or mounting in the airplane so that it will be ready for launching when desired. Then when the device is fired the sealing disc 131 is separated from the mortar end at the solder seal by the upward movement of plug 129 and the thrust member 127 as the projectile moves forward.

After a predetermined length of time, dependent upon the type of fuse 109 employed, the fuse will ignite the powder 80 within the pocket 79 of the plug 78 to cause the parachute and flare to be ejected from the projectile tube 41, as previously described and to cause the ignition of the candle.

When the device 21 is released, the device 21 is connected with the aircraft only through a cable which is connected also to the ring 34 of the igniter. The weight of the device causes the igniter 33 to be actuated and thereafter breaks the cable. The igniter ignites the fuse 122

which is spirally wound about the mortar tube 39 and extends through a hole in the bottom of the anchor 37 to connect with the quickmatch 120 as previously described. During the downward flight of the device 21, it is kept in a substantially vertical position by the fin assembly. After falling into the water, the device 21 initially sinks because of the momentum imparted thereto but is buoyed to the surface. The fuse 122 is of such length and type that the charge 93 will not be ignited to fire the projectile 45 until the device is buoyed on the surface of the water.

While the form of embodiment of the present invention as herein disclosed constituted a preferred form, it is to be understood that other forms might be adopted, all coming within the scope of the claim which follows:

We claim:

A pyrotechnic device adapted to be dropped from an aircraft into a body of water and thereafter float in an upright position comprising in combination, an elongated buoyant casing having an open top and a mortar base sealing the entire bottom of the casing, a mortar supported by the base within the casing and sealed therewith at the top of the casing, the peripheral portion of said mortar housed within the casing intermediate the base and top being spaced from the casing to provide a sealed air chamber between the casing and the mortar whereby the assembly is buoyant in water, said mortar base being of sufficient weight whereby the mortar extends vertically when the device is buoyed, an elongated cylindrical projectile contained within in said mortar, said projectile having a constant diameter throughout substantially the full length thereof, means for releasably retaining the projectile within the mortar prior to discharging the latter, said means including a removable plug in the upper end of the cylinder and an elongated spacer in said mortar and interposed between the top of the projectile and the bottom of the plug, said projectile containing a powder charge for expelling the projectile from the mortar, a delay fuse for igniting said powder charge housed within the sealed air chamber, and an igniter for firing the fuse.

HERBERT C. CLAUSER.
